Attorney.

UNITED STATES PATENT OFFICE

2,377,330

COMBINED LIQUID-LEVEL INDICATOR AND
CONTROLLER

Jonathan Dixon, Catonsville, Md.

Application April 12, 1944, Serial No. 530,656

3 Claims. (Cl. 200—84)

This invention relates to float-controlled devices, and especially to a combined liquid-level indicator and controller; and while this invention is especially designed for use in oil-feeding and burning systems, it is usable and practical in automatically regulating the liquid-level in any system where liquid is drawn from a tank solely by electrically operated means.

One object of this invention is to utilize a previously known form of liquid-level gauge or indicator, and, by slight modifications thereof and additions thereto, to adapt it to serve as a considerable portion of an effective and practical automatic means to cut off the electric current that supplies power for pumping liquid from a supply-tank, thereby minimizing the cost of an automatic low-level regulator without detracting from the utility of the liquid-level indicator.

Another object of the invention is to provide a compact unitary structure that is attachable directly on the supply tank, including a support or housing that contains an electric switch, and also includes a flexible diaphragm that is properly disposed and secured for preventing combustible or other detrimental gas from passing from the casing of the liquid-level indicator to the housing that contains the electric switch.

Another object is to provide, in a device of the character above-described, a unitary structure that includes an integral element that serves as a closure for an opening in the supply-tank, provided with means to removably secure it in its normal position over said opening, also provided with a guide-opening or bearing for the upright rod that carries the indicator-head, and also includes a socket in which is secured a fulcrum-rod to which the float-lever is pivotally connected; the float and the pivotal connections of the float-lever being of such dimensions and arrangement that they can be passed inward and outward thru the said opening when the said integral element is detached from the supply tank.

Other objects and important features are pointed out or implied in the following details of description, in connection with the accompanying drawing in which:

Fig. 1 is a vertical sectional view through the central part of a unitary supporting and guiding structure having therein certain features of my invention and other features that show the relation between those that control and those that are controlled, also showing screws for securing this unitary structure to the tank from which oil or other liquid is to be drawn by electric power to be controlled.

Fig. 2 is a vertical longitudinal sectional view through the tank, showing the float-lever and float in position at low-level of the liquid where the electric power is automatically cut off, also showing conventional forms of motor-generator and pump which latter is in open communication with the lower portion of the tank through an outlet-pipe.

Fig. 3 is a detail-assembly view of a modified form of actuating arm and connecting means on opposite sides of the diaphragm to which they are secured.

Fig. 4 is a top plan view of the main portion of an integral element such as shown in section in Figs. 1 and 2.

Referring to this drawing in detail, in which, similar reference numerals refer to similar parts throughout the several views, the invention is described in detail as follows.

20 A conventional form of tank 5 has its lower end or bottom portion in open communication with a pump 6 through the medium of an outlet-pipe 7; and a very important purpose of this invention is to prevent the lower-level of liquid from getting down to the lower end of the outlet-pipe, thereby to continually keep sufficient liquid in the tank to air-seal said outlet-pipe; for experience has shown that more than one serious disadvantage and cause of considerable expense and inconvenience results from admission of air or gas in the pump and in the pipes etc. that lead to and from the pump, especially in the case of oil-feeding to oil-burning devices.

25 A conventional form of motor-generator is shown at 8 connected to the pump 6 by a belt 9 and having electric terminals or wires 10 that lead to and from a conventional form of switch 11 which (in Fig. 1) is shown closed and normally secured in closed position by a spring-arm 12, these elements 11 and 12 being secured on a wall of a housing 13 whose bottom is centrally apertured at 13a and excentrically apertured at 13b, only two of the four apertures 13b being here in view; and around the central opening there is an annular ridge 13c for containing the upper end of a gage-glass or similar transparent casing-element 14 through which may be seen the depth-indicator or liquid-level indicator that consists of a rod 15 and an indicator-head 16 which latter has (preferably, but not essentially) an opening 16a therethrough.

30 The lower end of the transparent element 14 is seated on the integral element 17 whose annular ridge 17a surrounds the lower end of the element 14, and the element 17 has a central opening or

guide-bearing 17b through which the rod 16 is projecting a considerable distance (though here shown with a portion broken away). A pivot or float-actuated means 18 operatively connects the float-lever 19 to the upright rod or indicator-rod 15. A fulcrum-rod 20 has its upper end seated and secured in a socket 17c while its lower end is pivotally connected at 21 to the float-lever 19 that has the float 19a united therewith. The liquid 22, at its minimum level or lowest level, is supporting the float at its lowest position in Fig. 2, so the indicator head 16 is at the lowermost position shown in broken lines in Fig. 1, thereat keeping down the free end of the spring 12 so the switch 11 is then open, the motor-generator inactive, and the pump 6 not operating; so the owner or user then knows that the tank must be replenished with oil or liquid before more can be drawn from the tank; and can also know that no air has entered the pipes that connect to the pump, such knowledge being imparted by the motor-generator being stopped and inability to start it. Of course, however, the stopping of the electric power can be averted by care of the owner or user in continually watching the position of the indicator-head in the casing 14; but if the sufficient care is lacking, it does not result in the difficulties and expenses that results where the automatic regulator is lacking.

It should be understood that the element 17 is secured in place, where shown in Fig. 2, by means of screws 23 (in Fig. 1) that extend thru screw-holes 17d (Fig. 4) of which there are preferably four, though only two are seen in the drawing. Moreover, there are preferably four bolt-holes 17e to receive four bolts 24 of which only two are visible in the drawing; and these bolts extend through the holes 13b and are provided with nuts 24a; so the elements 13, 17, 24 and 24a are combined to form clamping means for tightly securing the marginal portion of the diaphragm 25 between the elements 13 and 14 so as to hermetically seal the opening 13a, for though the diaphragm is centrally apertured, such aperture is closed by a screw 26 (or 26a of Fig. 1) and a connecting element 27 in combination with nuts 28. The upper end of the element 27 is secured to the switch-controlling spring 12 by a screw 29 or by other appropriate means. An actuating arm 30 is secured to the screw 26 or 26a and depends therefrom and terminates in an abutment 30a at its lower end, such abutment being in a proper position to be pushed downward by its contact with the indicator-head when the latter moves to the position shown in broken lines near the element 17. The combination of elements 26, 27, 28 and 29; or 26a, 27, 28 and 29, may be more broadly termed connecting means to correlate the spring 12, diaphragm 25 and arm 30 so as to unite them into a dual-function means in cooperative relation to the elements 11 and 16 for effecting the opening of the electric switch by downward movement of the indicator-head to its lowermost position, such downward movement being float-controlled thru the medium of the in-

dicator-rod 15 and its pivot or connecting means 18 in cooperation with the elements 19, 19a, 20 and 21. The dual-function means not only effects opening of the switch, but also closes it by the inherent springiness of the elements 12 and 25, while preventing gas from passing from the chamber 14 to the switch 11 and thereby eliminating danger of a spark from the switch igniting gas in the switch-chamber or in the housing 13.

10 Though I have described this embodiment of my invention quite specifically, I have no intention to limit my patent-protection to these specific details, for the invention is susceptible of numerous modifications within the scope of the inventive ideas as implied and claimed.

I claim the following as my invention:

1. In a float-controlled device, a liquid-level indicator that includes a longitudinally movable rod having thereon an indicator-head, float-actuated means to operatively connect said rod to a float-lever, a supporting and guiding structure having therein a guide-opening thru which said rod extends, an electric switch secured to said supporting and guiding structure, spring-means on said supporting and guiding structure and normally in proper position to keep said switch closed, connecting-means operatively engaged with said spring-means, and an arm operatively engaged with said connecting-means and having an abutment in a proper position to become engaged with and moved by said indicator-head to a proper position for cooperating with said connecting means so as to bend said spring means from its spring-closing position.

35 2. In a float-controlled device for controlling an electric switch, a liquid-indicator that includes a vertically disposed rod provided with an indicator-head and with float-actuated means to connect it to a float-lever, and a transparent casing 40 in which the indicator-head is movable by said rod and float-actuated means, in combination with a flexible diaphragm, clamping means engaged with the margin of said diaphragm and casing so as to hermetically seal an end of the casing, a spring normally in proper position to keep the electric switch closed, an upright arm having an abutment at its lower end-portion and in a proper position to become engaged with and moved down with said indicator-head when said float-actuated means is lowered to a predetermined position, and connecting means engaged with said arm and diaphragm and spring so as to bend said spring from its switch-controlling position when the float-actuated means is lowered to said predetermined position.

3. The combination defined by claim 1, said supporting and guiding structure comprising a casing in which said indicator-head and abutment are supported, a diaphragm secured in a proper relation to hermetically seal the upper end of said casing, said connecting-means being secured to the central part of said diaphragm and extending upward to said spring and downward to said arm, for purposes specified.

JONATHAN DIXON.
